3 Claims. (Cl. 31—34)

The present invention relates to butter making churns in general, and more particularly to an improved churn of the type which is used for continuous production of butter.

It is an important object of our invention to provide a churn whose output may be varied at will, which is of very simple and space-saving construction, and which may be readily combined with conventional squeezing, washing, or kneading machines such as are used for further treatment of butter issuing from a churn.

Another object of the invention is to provide a churn of the just outlined characteristics which is constructed and assembled in such a way that its output may be varied not only when it is momentarily idle but also when it is in actual use.

A further object of the invention is to provide a churn which need not be taken apart when the operator desires to change its output and whose output may be varied infinitely between a maximal and a minimal value.

An additional object of the invention is to provide a churn of the above outlined characteristics which is constructed and assembled in such a way that at least some of its parts may be cleaned without necessitating even partial dismantling of the machine.

A nonconcurrent object of the invention is to provide a churn for continuous production of butter wherein the agitating member and the vessel for the agitating member need not change their positions with respect to each other when it becomes necessary to vary the output of the churn.

With the above objects in view, one feature of our invention resides in the provision of a butter making churn which comprises a preferably cylindrical vessel defining an internal chamber and arranged to receive starting material (such as milk or cream) at one end and to discharge butter and liquid at the other end thereof, a rotary agitating member extending into the chamber and comprising a shaft which is coaxial with the vessel, a motor drivingly connected with the shaft to rotate the agitating member whereby the material admitted at one end of the vessel is transformed into butter and liquid issuing at the other end of the vessel, and an arrangement for reciprocating the vessel in the axial direction of the shaft or for reciprocating the agitating member in the axial direction of the vessel to thereby vary the output of the churn whenever necessary.

In accordance with another feature of our invention, the output of the churn may be varied by placing a suitable insert into the chamber of the vessel so as to reduce the capacity of the chamber which is tantamount to a reduction in the output of the churn if the rotational speed of the agitating member remains unchanged. Similar results can be obtained by connecting the shaft of the agitating member with a variable speed electric motor so that the rotational speed of the agitating member is reduced when the operator desires to reduce the output of the churn.

The novel features which are considered as characteristic of the invention are set forth in particular in the appended claims. The improved churn itself, however,

2

both as to its construction and its method of operation, together with additional features and advantages thereof, will be best understood from the following detailed description of certain specific embodiments with reference to the accompanying drawings, in which:

FIG. 1 is a partly elevational and partly axial sectional view of a churn which embodies one form of the invention and whose output may be changed by varying the r.p.m. of the motor which drives the agitating member;

FIG. 2 is a similar partly elevational and partly axial sectional view of a somewhat different churn whose output may be varied by changing the capacity of the chamber in which the agitating member treats the starting material;

FIG. 3 is a further partly elevational and partly axial sectional view of a modified churn whose output may be varied by changing the axial position of the agitating member with respect to the vessel, the parts of the churn being shown in a position they assume when the output reaches a maximal value; and

FIG. 4 is a similar view of the modified churn whose parts are shown in a position they assume when the output is reduced to a minimal value.

Referring now in greater detail to the illustrated embodiments, and first to FIG. 1, there is shown a butter making churn A which comprises a stationary housing 10 mounted on a base 11 by means of legs 12 and accommodating a fixed cylindrical vessel 13 whose left-hand axial end is open, as at 14, so that butter and liquid issuing from the agitating or churning chamber 15 of the vessel may enter an outlet 16 to be discharged through a spout 17. This spout delivers butter and liquid to a washing machine of conventional design, not shown.

The chamber 15 accommodates a rotary agitating member or dasher 18 which comprises a shaft 19 carrying a series of axially parallel radially outwardly projecting blades or vanes 20 which extend into close proximity of the internal surface of the vessel 13. The vanes 20 are mounted on radial arms 21 which are fixed to the shaft 19, and this shaft is driven by the output shaft 23 of a variable-speed electric motor 22 whose casing 24 is bolted to the housing 10. The motion transmitting connection between the output shaft 23 and the driven shaft 19 comprises a suitable coupling 25 of any known design so that the motor 22 may be rapidly and conveniently disconnected from the agitating member 18 if the latter must be withdrawn for the purpose of inspection, repair, replacement or cleaning. The outlet 16 is preferably detachable from the housing 10 so as to provide access to the open end 14 of the vessel 13 and to the agitating member.

The shaft 19 extends through an antifriction bearing 26 provided in a vertical end wall 27 of the housing 10, and this end wall 27 is adjacent to the end wall 28 of the cylinder 13. The coupling 25 may be reached through a suitable door (not shown) provided in a tubular extension 29 of the housing 10 which is connected with the casing 24.

A conduit 30 which is led through the extension 29 and through the end walls 27, 28 serves to admit starting material into the chamber 15, and such material is thereupon agitated by the blades 20 as soon as the motor 22 begins to rotate the shaft 19.

In many large milk processing plants, there are times when it becomes necessary to change the output of one or more butter making churns. For example, it can happen that the output of a churn must be increased on a Monday so that the machine may process all of the cream or milk which has accumulated over the weekend, i.e., that the starting material may be processed in the morning shift. Furthermore, it is often necessary to

change the output of a churn by taking into consideration the composition of the starting material (i.e., the fat contents and the temperature of cream). On the other hand, it is also desirable to discharge butter and the liquid at a constant or nearly constant rate to avoid frequent adjustments and uninterrupted supervision of machines which receive butter and liquid from the churn. In other words, it is very desirable to construct the churn in such a way that its output may be varied infinitely between a maximal and a minimal value.

All an operator has to do in order to change the output of the churn A is to vary the r.p.m. of the motor 22 so as to reduce or to increase the rotational speed of the blades 20. By changing the r.p.m. of the driven shaft 19, we achieve the same result as by reducing or by increasing the effective axial length of the agitating member 18, i.e., the output of the churn is changed in a fully automatic way and such change may be brought about at the time when the churn is in actual use. The exact construction of the motor 22 forms no part of this invention; for example, we may utilize a variable-pole motor or we may vary the input (such as the frequency) of the motor in order to change its speed. The arrangement is preferably such that the r.p.m. of the output shaft 23 is variable infinitely between a maximum r.p.m. which corresponds to maximal output of the churn and a minimum r.p.m. which may correspond to a 50-percent drop in the output of the machine.

An important advantage of the churn A is that the entire chamber 15 may be utilized at all times irrespective of variations in the output.

FIG. 2 illustrates a slightly modified churn B which differentiates from the churn A mainly in that it comprises a different agitating member 118 with shorter blades 120 and with a shaft 119 which is detachably connected to the output shaft 23 by the coupling means 25. The right-hand section of the chamber 15 accommodates an insert or plug 131 having an axially parallel bore 134 which communicates with the conduit 30 so that the bore 134 may admit milk or cream into the remaining portion of the chamber 15. The insert 131 is provided with a circumferential groove for a sealing ring 132 which engages the internal surface of the cylinder 13. A second sealing ring 133 is provided around the discharge end of the conduit 30 to prevent escape of starting material into the space between the left-hand wall of the insert 131 and the end wall 28. This insert is further provided with an axial bore for the shaft 119.

By utilizing an agitating member with shorter blades and by reducing the capacity of the chamber 15, the output of the churn B is less than the output of the churn A. For example, the insert 131 may reduce the output from 1,000 kg./h. to 600 kg./h. Of course, the output may also be varied by changing the r.p.m. of the motor 22 even though it is equally possible to change the output solely by furnishing the churn of FIG. 2 with two, three or more different inserts each of which corresponds to a different output of the machine. In such instances the motor 22 may be replaced by a constant-speed motor.

When the user desires to increase the output to 1,000 kg./h., he removes the outlet 16 and, after detaching the shaft 119 from the shaft 23, withdraws the agitating member 118 and thereupon the insert 131. The insert need not rotate with the agitating member. A different insert of half the axial length of the insert 131 may be used to reduce the output to 800 kg./h.

It will be noted that, rather than by varying the output solely in response to changes in r.p.m. of the motor, the churn of FIG. 2 may change its output by changing the effective axial length of the agitating member and by changing the capacity of the vessel 13.

The churn of FIG. 1 or 2 may be modified by replacing the comparatively short output shaft 23 with a longer shaft which extends beyond the left-hand side

of the insert 131, as viewed in FIG. 2. The driven shaft 19 or 119 then assumes the form of a tube which is telescoped onto the output shaft. The driving connection between such telescoped shafts may assume the form of splines, diametral bolts or the like. If the driven shaft is a tube, the output shaft of the motor 22 may extend all the way to the open end 14 of the vessel 13.

FIG. 3 shows a churn C whose output may be varied by changing the axial position of the agitating member 218 with respect to the vessel 213. In this embodiment of our invention, the agitating member 218 and the motor 222 form a unit which is reciprocably guided along ways 235 secured to or forming part of the base 211 and extending in parallelism with the axis of the vessel 213. The casing 224 of the motor 222 comprises a slide 236 which is mounted in the ways 235 and the unit including the motor 222 and the agitating member 218 is reciprocable by an arrangement including a handwheel 237 which rotates a spindle 238 rotatably mounted in the base 211 and mating with a spindle nut 238a which is fixed to the casing 234. Of course, it is equally possible to fix the casing 224 to the base 211 and to reciprocate the vessel 213 with its housing 210 toward and away from the motor. This modification is so obvious that it can be readily comprehended without requiring a separate illustration.

In this embodiment of our invention, the shaft 219 of the agitating member 218 may be permanently fixed to the output shaft 223 of the motor 222 and, as shown in FIGS. 3 and 4, the output shaft 223 rotates in a bearing sleeve 239 which is fixed to the casing 224 so as to share axial movements of the agitating member 218. This bearing sleeve is provided with a bore 234 which communicates with the material admitting conduit 230 and with the internal chamber 215 of the vessel 213. The sleeve 239 carries a sealing ring 232 which engages the internal surface of the vessel 213. The construction of the outlet 216, of the spout 217, of the vanes 220 and of the arms 221 is the same as in the churn A or B.

When the operator desires to reduce the output of the churn C, the handwheel 237 is rotated in a sense to move the agitating member 218 in a direction to the left, i.e., from the position of FIG. 3 to the position of FIG. 4, whereby the left-hand end portions of the vanes 220 extend beyond the open end 214 of the vessel 213 so that the effective length of the agitating member is reduced with attendant reduction in the capacity of the vessel 213 and in the output of the machine. In other words, that portion of the agitating member 218 which extends outwardly from and beyond the open end 214 is not effective in the making of butter. The spindle 238 and the nut 238a enable an operator to move the agitating member to an infinite number of positions each of which corresponds to a different output of the churn. If desired, the motor 222 may be of the variable speed type even though any constant-speed motor will do since the output of the churn C may be varied solely by changing the axial position of the agitating member 218 with respect to the vessel 213 or vice versa.

An important advantage of the churn C is that the bearing sleeve 239 may be withdrawn entirely from the vessel 213 for the purpose of cleaning without necessitating even partial dismantling of the machine. The output shaft 223 rotates in suitable antifriction bearings 240 which are provided in the sleeve 239.

Without further analysis, the foregoing will so fully reveal the gist of the present invention that other can, by applying current knowledge, readily adapt it for various applications without omitting features that, from the standpoint of prior art, fairly constitute essential characteristics of the generic and specific aspects of this invention and, therefore, such adaptations should and are intended to be comprehended within the meaning and range 75 of equivalence of the following claims.

What is claimed as new and desired to be secured by Letters Patent is:

1. A butter making churn comprising cylindrical vessel means having an internal chamber and arranged to receive starting material at one end and to discharge butter and liquid at the other end thereof; rotary agitating means extending into said chamber and having a shaft which is coaxial with said vessel means; and electric motor having an output shaft drivingly connected with said first mentioned shaft so as to rotate said agitating means whereby the material admitted into said chamber is transformed into butter and liquid issuing from the other end of said vessel means; a bearing sleeve fixed to said motor and surrounding a portion of said first mentioned shaft, said sleeve being receivable in said chamber at said one end of the vessel means, and an arrangement for moving one of said means axially of the other means so as to vary the output of the churn, when necessary, said sleeve

extending into and being withdrawable from said chamber in response to reciprocation of said one means.

2. A churn as set forth in claim 1, wherein said sleeve is provided with a bore through which starting material is admitted into said chamber.

3. A churn as set forth in claim 1, wherein said agitating means further comprises a plurality of vanes adjacent to the internal surface of said vessel and arms connecting said first mentioned shaft with said vanes.
